(57) **CLAIM**

The ornamental design for a drum lug, as shown and described.

DESCRIPTION

1. Drum lug
- 1.1 : Perspective
- 1.2 : Front
- 1.3 : Back
- 1.4 : Left
- 1.5 : Right
- 1.6 : Top
- 1.7 : Bottom

The dashed broken lines illustrate portions of the drum lug and form no part of the claimed design; the dot-dashed lines in figs. 1.1 to 1.6 define boundaries of the claimed design and form no part thereof.
